Primary Examiner — Rosemary K Tarcza*Assistant Examiner* — Lacey Chey Bowman(57) **CLAIM**

The ornamental design for a Ptz outdoor camera, as shown and described.

DESCRIPTION

FIG. 1 is a first perspective view of a Ptz outdoor camera showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines shown in the drawings depict portions of the Ptz outdoor camera in which the design is embodied that form no part of the claimed design.
